UNITED STATES PATENT OFFICE.

GEORGE H. ULLMAN, OF NEW YORK, N. Y., ASSIGNOR TO L. PLAUT & COMPANY, OF NEW YORK, N. Y., A COPARTNERSHIP.

DESIGN FOR AN ELECTROLIER-BODY.

41,381.

Specification for Design.

Patented May 16, 1911.

Application filed February 28, 1911. Serial No. 611,535. Term of patent 7 years.

To all whom it may concern:

Be it known that I, GEORGE H. ULLMAN, a citizen of the United States, and a resident of the borough of Manhattan, city, county, and State of New York, have invented a new, original, and ornamental Design for an Electrolier-Body, of which the following is a specification, reference being had to the accompanying drawing, forming a part thereof.

In the drawing, Figure 1 is an elevation of an electrolier body showing my new design; and Fig. 2 is a bottom plan view thereof.

The design comprises a substantially hemispherical body having an extended edge

of beaded and ribbed form; and having represented on said body in relief a rosette surrounded by leaves radially arranged, around which are a plurality of grotesque heads having on each side thereof a cherub mounted on a dolphin.

I claim:

The ornamental design for an electrolier body, as shown and described.

Signed at New York city, county of New York, and State of New York, this 24 day of Feby. 1911.

GEORGE H. ULLMAN.

Witnesses:

JOHN L. LOTSCH,
GUSTAV A. SCHELLACK.
